[57] **CLAIM**

The ornamental design for a video game control seat, as shown, and described.

DESCRIPTION

FIG. 1 is a front elevation view of the video game control seat;

FIG. 2 is a back view;

FIG. 3 is a side view with the opposite side being a mirror image;

FIG. 4 is a top view;

FIG. 5 is a perspective view from the left side; and,

FIG. 6 is a perspective view from the right side.

The broken lines are for environmental purposes only and form no part of the claimed design.

FIG. 1

FIG. 2

FIG. 3

FIG. 4

FIG.5

FIG.6
